UNITED STATES PATENT OFFICE.

DAVID B. HANNA, OF CHICAGO, ILLINOIS.

METHOD OF AND APPARATUS FOR MAKING CONCRETE POSTS.

Application filed January 26, 1926. Serial No. 83,785.

This invention relates to a method of and apparatus for making concrete posts, poles or similar objects and is especially useful where a mold with a core is employed.

5 The principal object of my invention is to combine ramming or jolting with rotation and before entering into a detailed description I wish to point out, as is well known in the art, that ramming or jolting 10 concrete after it has been poured greatly increases the compactness or density of products. In posts used for lighting purposes it is, of course, often necessary to provide a raceway for the electric wires which, in an 15 ordinary molding operation, necessitates the use of a core.

With the foregoing in mind it is an object of my invention to ram or jolt a mold having a core and subsequently to rotate it in 20 order to force the concrete centrifugally away from the core and thereby release the core so that it can be easily withdrawn. Ramming or jolting would, of course, tend to pack the concrete so tightly around the 25 core that it could not be easily removed if at all. With my process and apparatus I rotate the mold immediately after the ramming or jolting operation which will still further increase the density of the concrete 30 and at the same time free the core.

More specific objects of the invention reside in the provision of an apparatus for jolting the mold in a substantially vertical position and then subsequently rotating it 35 without changing its position and the provision of a supporting table in an apparatus for carrying this out which can be jolted at will or rotated at will.

The foregoing together with such other 40 objects as may appear hereinafter or are incident to my invention I attain by means of a construction which is illustrated in preferred form in the accompanying drawings, wherein

45 Fig. 1 is a side elevation of my improved apparatus;

Fig. 2 is an enlarged section on the line 2—2 of Fig. 1;

Fig. 3 is an enlarged elevation partly in 50 section similar to the showing of Fig. 1 but illustrating only the lower end of my apparatus, namely the table; and

Fig. 4 is a section on the line 4—4 of Fig. 3.

55 Referring to the drawings it will be seen that the mold 5 is provided with a core 6

and that it stands upon the table indicated as a whole by the reference character A. The mold can be secured in any desirable way to the supporting shelf or ledge 7 of 60 the table by means of the bolts 8.

The upper end of the post mold is positioned and guided by the surrounding track 9 adapted to fit in the grooves of the rollers or wheels 9^a. Two of these rollers are stationary or fixed to the vertically moving 65 guide carriage 10 (see Fig. 2) while the third roller is mounted near the outer end of the curved retaining arm 11 which is adapted to be coupled to the curved retaining arm 12 70 by means of the pin 13. When it is desired to insert or release a mold the pin 13 is uncoupled and the arms 11 and 12 thrown back out of the way.

The guide carriage 10 is mounted for up 75 and down movement on the I-beams 14 and is connected over the pulley wheel 15 to the counterweight 16 by means of the cable 17. It will therefore be seen that my apparatus can readily take care of different heights of 80 posts. The guide carriage 10 can be clamped at any desired position by means of the bolts 18 and hand operated nuts 19 as will be clearly seen upon inspection of Fig. 2.

The table comprises the framework 20 with shaft 21 for the jolting operation and shaft 22 for the rotating operation, said shafts being substantially vertically disposed and parallel to each other. Transversely of the first two shafts in the bottom of the framework I provide the operating shaft 23 driven in any suitable manner as by a belt upon the pulley 24. The shaft 23 carries a cam 25 between the collars 26 and as this cam rotates it operates to lift the shaft 21 and the table top 7 through the medium of apparatus now to be described.

The cam works upon a roller 27 the axis 28 of which extends outwardly on each side through the bifurcated bearing plate 29 and the lifting arms 30. The plate rests upon the arms and the arms are pivoted to the frame at 31. The outer or free ends of the arms 30 are seated on the vertically movable spring supported sleeves 32 which are adapted to slide up and down on the stem or rod 33. The spring 34 below the sleeve 32 rests upon another sleeve 35 which has threaded engagement with the rod 33, as shown, so that upon rotation of the rod by 105 means of the hand wheel 36 it is possible to raise and lower the outer ends of the arms 110

30, the same being at all times cushioned by the springs 34. In this way the distance that the cam 25 lifts the table top 7 can be adjusted and the force of the impact on the 5 downward stroke regulated.

The thrust bearing 37 rests upon the plate 29, above which is the double cup shaped member 38 carrying on its upper face the lower end of the jolting shaft 21, the latter 10 taking the shape of a hollow tube as indicated in Fig. 4. The parts 29, 37, 38, 21, and 7 are held together in a vertical longitudinal direction by means of the rod 39 extending down through the shaft 21 and threaded 15 into the shouldered pin 40, the shoulder 41 of which engages the under faces of the plate 29 and the shoulder 42 the under face of the double cup shaped member 38.

On the downward stroke the table hub 43 20 takes against the shock absorbing packing 44 held in place by means of the band 45.

Surrounding the shaft 21 and secured thereto is the bearing sleeve 46 provided near its ends with suitable seats for the 25 annular ball bearings 47.

The hub 43 carries the gear 48 which is adapted to mesh with the gear 49 at the top of the rotating shaft 22. Rotating motion is imparted through the same shaft 23 which 30 raises and lowers the table top 7 by means of the gear 50 at the lower end of the shaft 22, gear 51 on the shaft 23, sleeve 52 to which the latter is secured and clutch mechanism 53 operated by the hand lever 54.

35 A summary of the operation is as follows:

A mold 5 with its core is secured to the table top 7 and guided at the top by the rollers 9. The shaft 23 is rotated and the table top 7 raised by the cam 25 after which 40 it drops back to the pad 44 and thereby jolts the mold. When the jolting is completed the arms 30 may be sufficiently raised by means of the hand wheel 36 as described to clear the path of the cam 25. The clutch 53 45 may then be thrown in and the table top 7 with the mold which it carries rotated until the centrifugal force compacts the concrete outwardly sufficiently to free the core 6.

50 My improved method gives a product of unusual density and strength and one which although it has had the advantage of a jolting operation still has within it a suitable raceway for wiring or piping necessary for lights.

55 I claim:

1. The herein described method of making concrete posts which comprises compacting the concrete in a mold and around a core and then rotating the mold at a speed sufficient to free the core from the concrete 60 by centrifugal action.

2. The herein described method of making concrete posts which comprises molding around a core, vertically jolting the mold 65 to pack the concrete, and rotating the mold

at a speed sufficient to free the core from the concrete by centrifugal action.

3. The herein described method of making concrete posts which comprises molding around a substantially vertical core, jolting 70 in upright position, and rotating at a speed sufficient to free the core from the concrete by centrifugal action.

4. An apparatus for making concrete posts comprising in combination, a mold 75 having a core, means for jolting the mold to pack the concrete received therein, and means for rotating the mold at a speed sufficient to effect separation of the packed concrete from the core due to the action of centrifugal force.

5. An apparatus for making concrete posts comprising in combination, a mold having a core, means for supporting and jolting the mold in a substantially vertical 85 position whereby to firmly pack the concrete therein, and separate means for rotating the mold whereby to set up a centrifugal action sufficient to free the core from the packed concrete.

6. In concrete post making apparatus the combination of a mold, a table for supporting the mold, means for jolting the table, and means operable subsequently to the 90 operation of said jolting means for rotating the table.

7. An apparatus for jolting and rotating a concrete post making mold comprising in combination, a table, a cam for jolting it, means for rotating the cam, a gear drive 100 for rotating the table, and a clutch for connecting said gear drive to the means for rotating the cam.

8. An apparatus for jolting and rotating a concrete post making mold comprising in 105 combination, a table, a shaft for jolting it, a shaft for rotating it, a common shaft for actuating both of said first two shafts, means for establishing and disabling the jolting connection, and means for establishing and 110 disabling the rotating connection.

9. Apparatus for making concrete posts comprising in combination, a mold, a table for supporting the mold in a substantially vertical position, means for jolting the table, means for rotating it, and means guiding the upper end of the mold without interfering with the jolting and rotating operations.

10. An apparatus for making concrete posts comprising, in combination, a mold, 120 means for jolting said mold in a substantially vertical direction, an annular member freely surrounding the upper end of said mold and rotatable therewith, and a plurality of rollers operatively associated with said member for preventing its vertical displacement without interfering with its rotative movement.

11. An apparatus for making concrete posts comprising, in combination, a mold, 130

means for jolting said mold in a substantially vertical direction, an annular member freely surrounding the upper end of said mold and rotatable therewith, a plurality of 5 rollers operatively associated with said member for preventing its vertical displacement without interfering with its rotative

movement, said member and rollers lying in substantially the same horizontal plane, and means for varying the elevation of said 10 plane.

In testimony whereof, I have hereunto signed my name.

DAVID B. HANNA.
